(57) **CLAIM**

The ornamental design for a scalpel handle sheath, as shown and described.

DESCRIPTION

FIG. 1 is a front perspective view of a scalpel handle sheath according to our design in a first configuration;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the scalpel handle sheath according to our design in a second configuration;

FIG. 9 is a front view thereof;

FIG. 10 is a back view thereof;

FIG. 11 is a right side view thereof;

FIG. 12 is a left side view thereof;

FIG. 13 is a top view thereof; and,

FIG. 14 is a bottom view thereof.

The broken lines showing a scalpel illustrate environmental subject matter that forms no part of the claimed design. Other broken lines shown in FIGS. 1-14 illustrate portions of the scalpel handle sheath that form no part of the claimed design.

1 Claim, 8 Drawing Sheets
